UNITED STATES PATENT OFFICE

2,460,594

BUILT-UP POST FOR WIRE BASKETS
AND THE LIKEWilliam Obernauer and Max Schuster,
New York, N. Y.

Application October 16, 1947, Serial No. 780,270

1 Claim. (Cl. 211—126)

1

The present invention relates to improvements in spacing and connecting means for wire baskets which are placed one above the other in spaced relation to one another or for other receptacles such as are used for papers, tools, and merchandise in offices, stores, shops and the like. More specifically, the present invention relates to a new and improved built-up post for wire baskets and the like.

One object of the present invention is the provision of a device of the character described which greatly facilitates a sturdy, safe detachable connection of wire baskets or the like one above the other in spaced relation to one another, so that they constitute a strong vertical structure that can be moved about without loosening or separation of the baskets from one another.

Another object of the present invention is the provision of a device of the character described which is light in weight and simple in construction and use, each post consisting of only one wire or of a thin rod which is bent and shaped in the manner described hereinafter, thus making it possible to manufacture and sell these built-up posts at a very reasonable price.

Still another object of the present invention is the provision of a device of the character described which can be used in a very simple manner for connecting wire baskets or the like to one another and which requires neither tools nor the application of any considerable amount of skill for attaching said baskets to each other or for detaching them from one another.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

In the accompanying drawings the preferred forms of the invention have been shown.

In said drawings:

Figure 1 is a top plan view of a preferred embodiment of our invention;

Fig. 2 is a front elevation of the same;

Fig. 3 is a side elevation of the same;

Fig. 4 is a top plan view of a wire basket with four built-up posts attached to its corner sections; and

Fig. 5 is a fractional front elevation of a stack of wire baskets connected to one another by

2

means of our new and improved built-up posts.

Similar reference characters refer to similar parts throughout the several views.

In the drawing the numeral 1 denotes a customary wire basket having a rim 2 and a wire body 3 and forming no part of our present invention.

Our present invention relates only to the built-up posts 4, each of which consists of one wire or of a longitudinal thin rod of steel or other metal, or of plastic material or the like. Said thin rod is bent at its half way point to form a slightly downwardly inclined V whose shanks 5 and 6 constitute the beginning of two identical sections of said rod. At the extremities of the shanks 5 and 6, said rod sections are bent laterally to a point where they are bent downwardly and partially back so as to form a pair of horizontally opposing loops 7 and 8. The inner lower extremities of the loops 7 and 8 are bent at 9 downwardly to the points 10. Between the points 9 and 10 are the straight downwardly diverging main portions 11 of the post which are longer than each basket 1 is deep. At the points 10 both sections of said thin rod are bent at substantially right angles rearwardly to the point 12, from whence the extremities of said thin rod are bent to form a pair of horizontally opposing hooks 14.

For connecting wire baskets 1 to one another, one built-up post 4 is required for each corner of each basket 1. One built-up post 4 after another is inserted with its loops 7 and 8 into a corner of the rim 2 of the upper basket 1 in the manner indicated in dash-and-dotted lines in Fig. 5. Then it is swung toward the next lower basket 1, so that the hooks 14 engage the rim 2 of said last mentioned basket. Thereby the main portions 11 are slightly spread apart, so that the hooks 14 will grasp the rim 2 beyond the second cross wire 3. When then the post is released in the position shown in full lines in Figs. 4 and 5, the resiliency of the thin rod will force the main portions 11 (and the hooks 14) toward one another, and the hooks 14 will firmly engage the rim 2 of the lower basket 1, while the downwardly inclined V formed by the half way portion of the thin rod (shanks 5 and 6) rests against the inner side of the corner of the rim 2 of the upper basket 1. In this way, after all the built-up posts 4 have been inserted, a sturdy connection of the upper basket 1 to the lower basket 1 is formed.

With our new and improved built-up post 4

two, three (as in the instance shown) or more baskets I can be connected to one another and kept in spaced relation to one another.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claim is intended to cover all of the generic and specific features of the invention herein described, and all statements of the scope of the invention which as a matter of language might be said to fall therebetween.

Having thus fully described our said invention, what we claim as new and desire to secure by Letters Patent is:

A device of the character described comprising 20 a longitudinal thin rod which at its half way point is bent horizontally to form a V whose shanks constitute the beginning of two identical sections of said rod and are bent at their extremities laterally to a point from whence they are 25 bent downwardly and partially back to form two horizontally opposing loops, the lower end portions of the loop forming parts of said sections

being bent downwardly to form the vertical downwardly diverging main portions of an upright post, at the lower end of said main portions both sections of the thin rod being bent rectangularly horizontally in the same plane, and the extremities of said thin rod being bent back and shaped as a pair of horizontally opposing resilient hooks, said loops being adapted for detachably engaging a corner portion of the rim of an upper basket, and said hooks being adapted for detachably engaging a corner portion of the rim of a lower basket of the same size as said upper basket and which is placed beneath the latter in spaced relation thereof, all substantially as described.

WILLIAM OBERNAUER.
MAX SCHUSTER.
